GARMENT RACK ATTACHMENT FOR IRONING BOARDS

Sadie T. Saltness, Dawson, Minn.

Application October 21, 1955, Serial No. 541,942

3 Claims. (Cl. 211—86)

This invention relates to a rack for supporting garments and other fabric articles, and more particularly has reference to a rack adapted to be detachably connected to an ironing board, mangle table, sewing table, or similar work surface so that articles may be supported by said rack on conventional garment hangers suspended from the rack, at locations convenient to the work surface.

In the ironing of dresses and other garments, or in the performance of other operations upon said garments, such as sewing, etc., it is a matter of some inconvenience to the housewife or other worker to leave the immediate vicinity of the work surface to hang the garment upon a conventional garment hanger and suspend the same from a support such as a clothes bar of a closet. Accordingly, the main object of the present invention is to provide a generally improved rack attachable directly to the ironing board or other work surface, which rack will be adapted for supporting a plurality of conventional garment hangers, on which the garments, after being ironed or otherwise acted upon, can be conveniently placed.

A more specific object is to provide a rack of the type referred to which will be particularly adapted to permit its swift and easy attachment to or detachment from the ironing table or other work surface, so that, following completion of the work, the rack can be removed and stored away waiting its next use.

Another object is to provide a rack as described which will be foldable following use into a compact, wholly planiform shape, so that it can be stored in a space substantially no wider than the thickness of any component part of the device.

A further object is to provide a device of the type referred to, which can be formed almost entirely from wire material at very low expense, thus to permit its manufacture at so low a cost as to enhance to a marked degree the commercial feasibility thereof.

Still another object is to provide a device of the type stated which will be swiftly attachable to ironing boards of various widths and thicknesses, and will be stably supported in an erect position upon said ironing board in each instance regardless of the differing thicknesses and dimensions of the ironing board or other support.

A further object is to so form and relate the several components of the device as to particularly adapt the same for distributing the weight of the supported articles and locate said articles in non-interfering relation with one another, in closely spaced relation to one side of the ironing board.

Other objects will appear from the following description, the claims appended thereto, and from the annexed drawing, in which like reference characters designate like parts throughout the several views, and wherein:

Figure 1 is a perspective view of a garment rack formed according to the present invention, mounted upon an ironing board, a portion of which is shown;

Figure 2 is a perspective view of the rack per se folded for storage;

Figure 3 is an enlarged side elevational view of the rack

2

in which the ironing board has been shown in transverse section, the dotted lines showing the rack adjustably flexed for mounting upon an ironing board of greater width than that shown in full lines;

5 Figure 4 is a fragmentary view similar to Figure 3 showing the device mounted upon a metal ironing board; Figure 5 is an enlarged detail sectional view on line 5—5 of Figure 3;

Figure 6 is a sectional view on line 6—6 of Figure 3, 10 the scale being reduced below that used in Figure 5 but being greater than that of Figure 3; and

Figure 7 is a sectional view similar to Figure 6, the ironing board not being shown, the spreadable support rods being shown in folded or collapsed positions.

15 The reference numeral 10 generally designates a conventional ironing board. In Figures 1—6, the ironing board illustrated is of wooden construction, and would be, of course, covered with suitable padding, not shown. In this connection, although the garment rack has been 20 illustrated in association with an ironing board, as will presently appear it can be erected with equal facility upon any of various other work surfaces, such as sewing tables, etc.

The device constituting the present invention has been 25 generally designated at 12, and includes support means projecting upwardly from and detachably connectable to the ironing board, said support means being formed from a single length of stout wire material bent intermediate its ends to provide a vertical leg 14 and an inclined support leg 16. The support legs 14, 16 are disposed at an acute angle to one another, and as shown in Figure 3, cooperate with the ironing board in defining a right triangle. At the apex of the triangle, where the legs 14, 16 are integrally joined, a spring means is defined, so that the 30 legs 14, 16 can be springably shifted away from one another against the restraint of the inherent spring tension thereof, to accommodate the same to ironing boards of different widths. This is shown to advantage in dotted lines in Figure 3, wherein the legs 14 are shown flexed 35 outwardly, so that the support legs are spaced apart at their lower ends a distance greater than that shown in full lines in this figure of the drawings. By reason of the construction illustrated and described, the support means 40 may be appropriately considered as being approximately 45 of inverted V-shape.

At its lower end, the support leg 14 is integrally formed with a curved extension 18 projecting toward the lower end 20 of the support leg 16 and adapted to engage against the lower edge of the associated side of the ironing board.

The lower end portion 20 of the leg 16 is also of curved formation, although the curvature is substantially more pronounced than that of the extension 18. This provides an inwardly extending, lateral projection of the lower end 55 of the inclined support leg, terminating at its free end in a hook-like or rounded part 22 bearing against the underside of the ironing board, with the portion 20, where it merges into the leg 16, being frictionally engaged against the adjacent side edge of the ironing board.

60 In use of the device, the legs 14, 16 are disposed in a common vertical plane, normal to that of the ironing board and substantially perpendicularly related to the longitudinal center line of the ironing board.

65 Adjacent the extension 18, there is crimped about or otherwise fixedly secured to the generally vertical support leg 14 a sleeve 24, said sleeve as shown in Figure 5 being integrally formed with side by side channel portions 26.

A pair of swinging support rods or braces provide feet 70 upon the leg 14, and have been designated at 28, 30 respectively. These are also formed from wire material, and at their free ends have short, upwardly extending extensions 32, 34 so as to prevent the outer extremities

of the support rods from catching on the cloth covering of the ironing board.

At their inner ends, the support rods are integrally formed with upwardly extending portions 36, 38 respectively rotatably engaged in channel portions 26 of sleeve 24. Since the portions 36, 38 extend parallel to the leg 14, this swingably mounts the support rods for movement toward and away from one another as shown in Figures 6 and 7, in a common plane perpendicular to the length of the support leg 14.

At the upper ends of portions 36, 38 there are formed laterally projecting, oppositely curved fingers 40, 42 adapted to engage against diametrically opposite surfaces of the support leg 14 when the rods 28, 30 are swung away from one another to their use positions as in Figure 6. The fingers thus provide stops limiting the outward swinging movement or spreading of the support rods, and when the support rods have been adjusted outwardly from one another to their maximum extent, they are disposed in acute-angular relationship in engagement with the top surface of the ironing board 19.

Due to this arrangement, the device, when it is to be used, can be swiftly attached to the ironing board, merely by flexing the leg 14 outwardly a distance sufficient to permit engagement of the inwardly curved lower end portions of the support legs with opposite longitudinal edges of the ironing board in the manner shown in Figures 1 and 3. Then, the support rods 28, 30 are swung outwardly from one another from their Figure 7, folded positions, in opposite directions out of the plane of the support means 14, 16. This firmly supports the device in its use position, holding the same against lateral tilting in either direction.

Welded or otherwise fixedly secured to the upper end portion of the support leg 14 is an approximately C-shaped upper garment support member 44, the bight 47 of which is affixed to the support leg 14 in longitudinally contacting relation thereto, with said bight extending a short distance above the upper extremity of the leg 14. Integral with the bight at opposite ends thereof are horizontally, outwardly extending garment hanger support arms 46, 48 of different lengths, the upper one of said arms being longer than the lower, the arms terminating at their free ends in upwardly projecting extensions providing stops to limit accidental movement of the garment hangers, not shown, off the support arms. The different lengths of the support arms are adapted to permit the garment hangers to be disposed in adjacent, vertical planes, in non-interfering relationship with one another, at the outer ends of the arms 46, 48.

Below the upper support member 44 there is provided a generally C-shaped lower support member 50, secured to leg 14 in the same manner as member 44, and having an upper support arm 52 longer than the lower support arm 54 thereof. Arms 52, 54 terminate at their free ends in outwardly extending fingers or projections, and as will be noted in Figure 3, the arm 52 is shorter than the arm 48 of the upper member. As a result of this arrangement, garment hangers can be suspended from the several arms 46, 48, 52, 54, in closely spaced vertical planes, without interference with each other, and garments can be placed upon said hangers after they have been ironed or after other work has been performed thereon. The supported garments are all disposed in closely spaced relation to the support 10, so as to locate the weight of the supported garment as close to the support means 14, 16, as possible and so as, further, to conveniently locate the garments where they will not interfere with the performance of the work.

The support rods 28, 30 of course, aid in supporting the weight of the garment, and also prevent tilting of the device when it is in use. Any tendency of the device to tilt in its own plane is resisted, of course, by engagement of the curved extensions 18, 20 against the underside of

the ironing board, at opposite sides thereof, and by reason of the construction illustrated, although the device is quite light and inexpensively constructed, it is adapted to support in a very stable manner, substantial weight.

When the device is not in use, it can be swiftly detached from the ironing board, after which the legs 28, 30 fold into the common plane of the support legs 14, 16, hanger support member 44, and support member 50. All components of the device are now in a common plane, in effect, so that a completely planiform device results as shown in Figure 2, which can be stored in a space of very low transverse dimension.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles, it being considered that the invention comprehends any minor change in construction that may be permitted within the scope of the appended claims.

What is claimed is:

1. A garment rack for attachment to ironing boards and the like, comprising: a support having the general shape of an inverted V and including a pair of coplanar support legs respectively extending upwardly from and engageable with opposite sides of an ironing board, said legs being formed at their lower ends with inwardly directed extensions adapted to engage the underside of said board; a plurality of garment support arms projecting laterally, outwardly from one of said legs in the plane of the legs; and a pair of support rods extending laterally, inwardly from said one leg above the extension thereof for engaging against the upper surface of said board.

2. A garment rack for attachment to ironing boards and the like, comprising: a support having the general shape of an inverted V and including a pair of coplanar support legs respectively extending upwardly from and engageable with opposite sides of an ironing board, said legs being formed at their lower ends with inwardly directed extensions adapted to engage the underside of said board; a plurality of garment support arms projecting laterally, outwardly from one of said legs in the plane of the legs; and a pair of support rods extending laterally, inwardly from said one leg above the extension thereof for engaging against the upper surface of said board, said rods being swingably mounted upon said one leg for movement between an inoperative position in which the rods are extended in longitudinally contacting relation in the common plane of the leg, and a use position in which the rods are angularly related to one another and project in opposite directions out of said plane.

3. A garment rack for attachment to ironing boards and the like, comprising: a support having the general shape of an inverted V and including a pair of coplanar support legs one of which is extended approximately vertically and the other of which is inclined substantially from the vertical, said legs respectively extending upwardly from and being engageable with opposite sides of an ironing board and being formed at their lower ends with inwardly directed extensions adapted to engage the underside of said board; a plurality of garment support members of generally C-shaped configuration projecting laterally, outwardly from said one leg, each member including a bight fixedly secured to said one leg in longitudinally contacting relation therewith and a pair of substantially horizontal disposed support arms, the arms of each pair being of different lengths with the longer arm being disposed above the shorter arm and the longer arm of the lowermost member being shorter than the shorter arm of the member next above the same, said members being spaced longitudinally of said one leg; and a pair of support rods swingably mounted upon said one leg at a location between the lowermost garment support mem-

ber and the board-engaging extension of said one leg, said rods being swingable in a plane normal to the length of said one leg between an inoperative position in which the rods are disposed in longitudinally contacting relation substantially in a common plane of the legs and members, 5 and a use position in which the rods are acutely related, and project in opposite directions out of said plane.
